Inventor:
J. Monroe Hendricks

United States Patent Office.

J. MOORE HENDRICKS, OF PHILADELPHIA, PENNSYLVANIA.

Letters Patent No. 73,716, dated January 28, 1868.

RICE-HULLING MACHINE.

The Schedule referred to in these Letters Patent and making part of the same.

TO ALL WHOM IT MAY CONCERN:

Be it known that I, J. MOORE HENDRICKS, of Philadelphia, Pennsylvania, have invented certain new and useful Improvements in Machines for Hulling and Dressing Rice; and I do hereby declare that the following is a full and exact description of the same, reference being had to the annexed drawings, forming part hereof, and to the letters of reference marked thereon, in which drawings—

Figure 1 is a vertical section of the machine.

Figure 2, a longitudinal vertical section of the chafing and polishing-cylinders *o* and *u*, fig. 1.

My invention relates to machines for hulling and dressing rice, and consists, first, of certain arms, which project radially from the movable stone of the hulling-mill, in combination with an annular surrounding chamber, the inner surface of the circumscribing wall of which is lined with fine-wire cloth, said chamber being provided with an aperture, located near the top of said wall, for the gradual escape of the hulled rice; second, of a cylinder for chafing the cuticle off of the grains of rice, said cylinder being lined with fine-wire cloth, and having a longitudinal shaft, which is provided with corrugated curved arms, projecting from said shaft on opposite sides, so as to break spaces; third, of the combination of a mortar and pestle with said chafing-cylinder, and a brushing-cylinder, hereinafter described.

To enable others skilled in the art to make and use my invention, I will proceed to describe its construction and mode of operation.

In fig. 1, *A* represents the frame of the machine. *a* represents the hopper, *b* the stationary stone, and *c* the movable stone of the hulling-mill. *d*, a cylinder, which surrounds the stones *b* *c*, and encloses an annular chamber, *e*. *f* is a shaft, working in a step at its lower end, carrying a pulley, *g*, for the belt by which it is turned. The upper end of said shaft passes through the stationary stone *b*, and is fastened to the movable stone *c* by means of a cross-head, *h*. All these parts are in the usual form. I provide the movable stone *c* with one or more arms, *i*, and I line the inner surface of cylinder *d* with fine-wire cloth, and I make an aperture, *j*, through the cylinder *d*, near its top, for the gradual escape of the mixed rice and hulls. *k* is a mortar; *l*, a pestle, with a projection, *l'*; *m*, a shaft, with projections *m'*. This shaft has bearings in the frame of the machine, and carries at one end a pulley (not shown in the drawings) for the belt, by which it is connected with a driving-shaft. *n* is an aperture, leading from the bottom of the mortar *k* into the top of the chafing-cylinder *o*. This cylinder *o* consists of a wooden framework, with solid ends, the inside face of said frame being covered with fine-wire cloth. *p* is a shaft, which has bearings in each end of said frame. The shaft *p* is provided with two or more curved corrugated arms, *q*, arranged so as to break spaces, and thus more completely chafe the rice. The aperture *n* is closed with a slide, which corresponds with it in form. *r* is an aperture, leading from the bottom of the chafing-cylinder *o*, into a receiving-chamber, *s*, fig. 2. *t* is another aperture, leading from chamber *s* to the tapered cylinder *u*. The aperture *t* is closed with a slide, *v*, fig. 2. The cylinder *u* is composed of a wooden framework, with solid ends, the inner face of the frame being covered with fine-wire cloth. *w* is a shaft, with bearings in the ends of cylinder *u*. Shaft *w* carries a tapered drum, *x*, covered with sheep-skin, with the wool on, and is wrapped with a textile rope spirally, as shown in fig. 2. *y* is a pulley for a belt, by which shaft *w* is connected with a driving-shaft. *z*, fig. 2, is an aperture, by which the rice escapes from cylinder *w*.

The rice which is intended to be treated is placed in the hopper *a*, and thence drops down through the eye of the movable stone *c*, passes between the two stones, and is thrown out into the annular surrounding chamber *e*, and is worked around and upward in mass by the arms *i*, the grains rubbing against each other, and against the rough surfaces of the chamber and moving stone. As soon as the rice works up as high as the bottom of aperture *j*, it begins to discharge through said aperture. This operation removes the hull from the rice, and loosens the cuticle, preparatory to the further operations, which I will now describe. The rice is next put into the mortar *k*, where it is pounded by the automatic pestle, *l*. The slide is withdrawn from the aperture *n*, and the rice runs down into cylinder *o*, where it receives additional attrition, the revolving arms *q* working through it, and rubbing it against the wire lining, throwing off the cuticle through the meshes of the wire cloth. After the cuticle has been entirely removed from the rice by the operations last described, the slide *v* is withdrawn, and the rice runs down into the chamber *s*, and thence, through the aperture *t*, is fed into the smaller end of the tapered cylinder *u*. Here it is polished by means of the revolving covered drum *x*, and escapes through the aperture *z*, fig. 2, in a thoroughly-cleaned condition.

The cylinder *d* might be made of stone, and then the lining of its inner surface with wire cloth could be dispensed with. The mortar and pestle are constructed of the materials usually employed in the making of such articles for the purpose herein described.

Having thus described my invention, I claim, and desire to secure by Letters Patent—

1. The cylinder *o*, in combination with its shaft and corrugated curved arms *q*, for chafing the cuticle, and removing the same from the rice, substantially as set forth.
2. The combination of the mortar and pestle *k l*, the cylinder *o*, (with its shaft, *p*, and corrugated arms *q*,) and the polishing-cylinder *u*, with its covered drum, all constructed and arranged in the manner and for the purpose substantially as set forth.

J. MOORE HENDRICKS.
